UNITED STATES PATENT OFFICE.

EMORY A. TRUSSELL, OF NEW YORK, N. Y., ASSIGNOR TO BOORUM & PEASE LOOSE LEAF BOOK COMPANY, OF NEW YORK, N. Y., A CORPORATION OF MISSOURI.

LOOSE-LEAF BINDER.

1,150,719.

Specification of Letters Patent. Patented Aug. 17, 1915.

Application filed March 5, 1915. Serial No. 12,345.

To all whom it may concern:

Be it known that I, EMORY A. TRUSSELL, a citizen of the United States of America, residing in the borough of Manhattan, city, 5 county, and State of New York, have invented certain new and useful Improvements in Loose-Leaf Binders, of which the following is a specification.

The main object of my invention is to 10 provide a loose-leaf binding device, having the metal parts very simple in construction, economical to manufacture and easily applied to the book cover. This object I attain by the construction which I will now de- 15 scribe.

In the accompanying drawing, Figure 1 is 20 a perspective view of the metal parts of my invention in their simplest form, one of the spring plates being shown detached and in section; Fig. 2 is a transverse sectional view, drawn to a larger scale, showing the metal parts applied to the book back, and with the leaf-holding rings or prongs closed; Fig. 3 is a plan view, with one of the spring plates 25 removed; Figs. 4 and 5 are sectional views on the lines 4-4 and 5-5, respectively, Fig. 3, and drawn to a larger scale; and Fig. 6 is a transverse section of a modification.

Referring to Figs. 1 to 5, it will be seen 30 that in this the simplest form of my invention, the metal parts of the binder consist of four parts only, namely, two like parallel bars A, A¹, each provided at each end with matching half rings or prongs a, a, and 35 a¹, a¹, and one or more spring covers B and B¹ fitting over the two bars A, A¹. The curved prongs a, a, (a¹, a¹) are formed in one with their respective bars A (A¹), and they may conveniently be formed from rods 40 of flattened oval cross section as seen in the drawings, one edge of each bar bearing against the corresponding edge of the other bar, as seen in Figs. 2 and 3. At their adjacent edges I form coöperating recesses 45 and spurs. Thus as shown in Figs. 1, 3 and 5, I strike up from the edge of bar A, a spur 10 on the upper side, and a recess 11 immediately under it on the lower side. At a corresponding point on what will be the adjacent edge of the bar A¹ I swage downwardly a recess 12 to receive the spur 10, and by the same operation form on A¹ a spur 13 to enter recess 11 on bar A. Similar 50 corresponding spurs and recesses, but re-

versed, are formed in the adjacent edges of 55 the bars near by, as at the section line 4-4, Fig. 3, and as shown in Fig. 4. These sets of spurs and recesses thus mesh and retain the bars in engagement under the action of the embracing springs B and B¹. 60

In the drawing I have shown two separate spring plates B and B¹, each consisting of an inverted U-shaped plate of sufficient width to extend over the pair of bars A, A¹, and in order that the outer edges of the latter may find proper bearings against the side walls of the springs B, B¹, I prefer to 65 swage the edges of the bars so as to force the metal outward to form projecting fins 20 and 21, Figs. 1, 2 and 3. Indentations 22 70 are at the same time formed in the parallel side walls of the springs B, B¹, to take under these projecting fins 20 and 21. The bars A and A¹ are thus hinged to each other and to the side walls of the plates B, B¹ with a 75 toggle action, and the tops of the spring plates B and B¹ are curved so as to provide the required elasticity for the rocking of the toggle from the positions shown in Fig. 2 to the open position of the prongs or half 80 rings.

The lower edges of the side walls of the plates B, B¹ are provided with pointed teeth 25 such that they may be driven into the back C of the book cover, Fig. 2, and be 85 clenched there to secure the described metal parts to the book.

I may provide a cover plate D, Fig. 6, which is arranged to cover the whole length of the bars A, A¹, and the springs B, B¹, 90 and to extend beyond the prongs a, a¹. This cover plate has lateral slots 27, 28 through which the prongs a, a¹, may pass. These lower edges of the side walls of this cover plate are provided with teeth 26, similar to 95 the teeth 25, to be driven into the back C. Where this cover plate is used, the teeth 25 on the springs B, B¹ may be omitted.

I claim as my invention:—

1. A loose-leaf binding device, comprising 100 bars carrying curved prongs, with pairs of reversed spurs and recesses at the adjacent edges of the bars and spring means to act upon the outer edges of the bars with toggle effect.

2. A loose-leaf binding device, comprising 105 bars carrying curved prongs, with pairs of reversed spurs and recesses punched out on

the adjacent edges of the bars and spring means to act upon the outer edges of the bars with toggle effect.

3. A loose-leaf binding device, comprising 5 bars carrying curved prongs, with coöperating spurs and recesses at the adjacent edges of the bars, and projecting fins on the outer edges of the bars and a spring plate means embracing the bars and bearing against the 10 fins.

4. A loose-leaf binding device, comprising 15 bars carrying curved prongs, with coöperating spurs and recesses at the adjacent edges of the bars, projecting fins punched out at the outer edges of the bars and a spring plate means embracing the bars and bearing against the fins.

5. A loose-leaf binding device, comprising bars carrying curved prongs, and hinged

together at their inner edges, projecting fins 20 at the outer edges, a spring plate means embracing the bars and bearing against said fins, said plates having indentations to take under the fins.

6. A loose-leaf binding device, comprising 25 bars carrying curved prongs and hinged together at their inner edges, and a spring plate means extending over the bars and bearing against their outer edges, said spring plate means having teeth adapted to 30 be driven into the back of the book cover.

In testimony whereof I have signed my name to this specification, in the presence of two subscribing witnesses.

EMORY A. TRUSSELL.
